(57) **CLAIM**

The ornamental design for an electronic sensor housing, as shown and described.

DESCRIPTION

FIG. 1 is a top, front, three-quarter perspective view of the electronic sensor housing for mounting in a corner or against a flat surface;

FIG. 2 is a front plan view thereof;

FIG. 3 is a rear plan view thereof;

FIG. 4 is a left plan view thereof, showing a sloped right-facing front portion;

FIG. 5 is a right plan view thereof, showing the sloped front portion facing left;

FIG. 6 is a top plan view thereof;

FIG. 7 is a bottom perspective view thereof, illustrating how the front face of the electronic sensor housing is seen when viewing the electronic sensor housing from the bottom; and,

FIG. 8 is a front, bottom, perspective view thereof.

The broken line showing is included for the purpose of illustrating portions of the “article” and forms no part of the claimed design.
